United States Patent Office.

WILLIAM H. NOBLES, OF ST. PAUL, MINNESOTA, AND MILTON V. NOBLES,
OF ELMIRA, NEW YORK.

Letters Patent No. 74,410, dated February 11, 1868.

IMPROVEMENT IN STEAM-GENERATORS.

The Schedule referred to in these Letters Patent and making part of the same.

TO ALL WHOM IT MAY CONCERN:

Be it known that we, WILLIAM H. NOBLES, of St. Paul, Ramsey county, State of Minnesota, and MILTON V. NOBLES, of Elmira, Chemung county, State of New York, have invented an Improved Spark-Arrester and Smoke-Consumer; and we do hereby declare the following to be an exact description thereof, reference being had to the accompanying drawings, and to the letters of reference marked thereon, making a part of this specification.

Figure 1 represents a longitudinal section of the boiler, flues, and fan.

Figure 2, a top view of the end of the boiler, connecting-flues, fan encased with a water-chamber surrounding the outside of the fan-case, and the perforated shaft of the fan-wheel.

Figure 3 represents a top view of the water-chamber, with its wheel for cleaning out the sediment of cinders and ashes.

The object of our invention is to conduct the heat and smoke from and to the fireplace in one continuous course, so that the smoke shall pass through the grates, assisting the combustion of the escaped gases, giving a greater degree of heat, which is controlled by the spray of commingled steam and water, whilst the cinders and ashes are being regularly and continually discharged, so that the course of the draught is not interrupted.

A represents a steam-generator; B, the fire-chamber; C, the grate running lengthwise with the boiler. D is an air-chamber underneath the grate. E represents the water in said chamber, in which the cinders and ashes are collected as they pass through and from the inclined tube F, and also the cinders and ashes as they fall from the grates above. A revolving wheel, G, operates in the bed of the chamber E for the purpose of discharging the cinders and ashes from the chamber E, through the aperture and pipe H. The wheel G can be driven by bevel or other gearing I. J J are the flues conducting the heat, smoke, and cinders from the fireplace B, as indicated by the arrows, and connecting with the double-cased fan-wheel K, the shaft of the wheel being hollow and perforated to admit a spray or jets of water upon the wheel to keep the wheel cool, and also to wet the cinders, ashes, and dust that may be carried from the fireplace into the fan-chamber, and then blown into and carried off through the tube F to the water-chamber E; the tube F being sufficiently large to carry off the smoke, and also to allow the spray of commingled steam and water to condense and pass through the tube. The fan-wheel K is encased and enclosed in a separate outside case, L, which is to contain water, to prevent the inner case and wheel from becoming injured by intense heat, or we may use an air-pump in place of the fan, if deemed proper. A waste-pipe, M, connected with the fan-chamber, may be used to supply heat to a train of cars, or to any room, and the other end of waste-pipe is intended to be joined with the water-chamber E, so as to return the smoke or heat back to the fireplace, or be disposed of as may be deemed necessary. N is a chimney or pipe, located above the fireplace, with a damper that is intended to be used for the smoke to pass off whilst the fire is being made to start the engine, wherever required.

What we claim as our invention, and desire to secure by Letters Patent, is—

1. The combination of the fan-wheel case K and the water-chamber L, as herein described and set forth.
2. We also claim the combination of the water-chamber E and wheel G, as herein described and set forth.
3. We also claim the arrangement of the inner and outer cases K and L, wheel G, discharge-opening H, flue F, and chamber D, whereby to conduct the heat and smoke from the fireplace and back, in one continuous rotating course, substantially as herein set forth.

W. H. NOBLES,
M. V. NOBLES.
